UNITED STATES PATENT OFFICE.

GEORGE WALKER, OF NEWTON CENTER, MASSACHUSETTS.

NON-PRINT AND NON-COMPUTE MECHANISM FOR TYPOGRAPHICAL COMPUTING-MACHINES.

1,138,161.

Specification of Letters Patent.

Patented May 4, 1915.

Application filed July 25, 1912. Serial No. 711,503.

To all whom it may concern:

Be it known that I, GEORGE WALKER, a citizen of the United States, and resident of Newton Center, in the county of Middlesex 5 and State of Massachusetts, have invented new and useful Improvements in Non-Print and Non-Compute Mechanism for Typographical Computing - Machines, of which the following is a specification.

- 10 This invention relates to typographical computing machines, and its object is to provide mechanism by which the ordinary and usual operation of the machine from the keyboard will cause the machine to print 15 without computing, or to compute without printing, at the will of the operator, thus providing a machine adapted for both computing and printing which may be instantly transformed into a non-printing computing 20 machine, or a non-computing printing machine, as desired.

The invention in its broadest aspect is applicable to typographical computing machines generally, but for the purpose of illustration I will show it as applied to the typographical computing machine described in Letters Patent of the United States No. 996,173, issued to me June 27, 1911, and more particularly to that form of said machine described at page 30 of said patent beginning at line 65. For convenience I will use in the present specification the same reference numerals as are used in my said former patent so far as they are applicable.

30 In the accompanying drawings, which illustrate certain embodiments of the invention,—Figure 1 is a side view, partly in vertical longitudinal section through the machine, showing my new non-printing and 35 non-adding mechanism, and such parts of the typographical computing machine as are necessary to an understanding of the construction and operation of the present invention; Fig. 2 is a side elevation viewed 40 from the reverse side of Fig. 1, showing certain of the operating parts embodying my invention; and Fig. 3 is a view similar to that shown in Fig. 1, but illustrating certain modifications in the invention to adapt it to 45 a modified form of the computing machine.

It will be understood, by referring to my said Patent No. 996,173, that when a numeral key is depressed crank 560 is rotated, pulling downward bar 561 and causing latch 562 to lift lock 18 out of the teeth of gear

wheel 1, and set pawl 11^A into the teeth of said gear wheel by the swinging of tail piece 18^A. Pawl 11^A is then swung by the further depression of the key, about shaft 4 as an axis, thus rotating gear wheel 60 1 and type wheel or numeral wheel 3 a distance corresponding to the value of the key being depressed, thereby performing the addition. At the same time type plate 37 will be swung upward on shaft 4 as an axis until 65 the type corresponding to the value of the key being depressed stands opposite the printing hammer 109, and hammer 109 will be operated to print the amount added, by striking said type on type plate 37. The 70 mechanism for operating said hammer 109, comprises rod 33—36 which is pulled toward and left by crank 560 when a key of the keyboard is depressed, swinging piece 103 in the same direction and lifting latch 106 75 which engages arm 109² on hammer 109, causing the hammer to be thrown back toward the right until the nose of latch 106 slips off arm 109², whereupon the hammer will fly forward under the influence of its 80 spring to print from the type plate the amount corresponding to the value of the key depressed. The parts thus far described may all be of the same construction and mode of operation as the corresponding 85 parts described in my said former patent.

In order to render the machine a non-printing computing machine or a non-computing printing machine, I provide means for disconnecting or disabling at will the 90 train of mechanism for actuating the main gear wheels 1, or the train of mechanism for actuating the hammers, without in either case affecting the other. As the actuation of gear wheel 1 depends upon the movement 95 of parts 18 and 18^A by latch 562, the elimination of the adding or computing functions of the machine may be accomplished by disconnecting or disabling the latch 562; and as the actuation of the hammer 109 depends 100 upon latch 106, the elimination of the printing functions may be accomplished by disconnecting or disabling the latch 106. These two results are preferably accomplished by 105 a single hand-operated lever, controlling the following mechanism (Figs. 1 and 2):—705 is a shipper, consisting, as herein shown, of a hand-operated, bell crank lever hung on shaft 4 with its upper arm projecting through a slot in the cover of the machine, 110

and forming a hand lever which may be swung forward or backward. A rod or link 706 connects lever 705 with a lever arm 707 (Fig. 2) which is fastened solidly on the end of shaft 708 just outside of the side frame B' of the machine. Shaft 708 is a shaft projecting through side frame B', and into a similar side frame opposite (not shown) turning in said side frame. Arm 709 is fastened solidly on said shaft 708 just inside the side frame B', and a duplicate of said arm 709 is fastened solidly on said shaft just inside the opposite side frame. Rod 710 (Fig. 1) extends between said arm 709 and its duplicate, across the tails 562^A of all the latches 562, said rod 710 having its ends secured in the ends of said arms. It will be understood that there is a latch 562 for each column of the machine.

When hand lever 705 is thrown forward in the direction of the arrow, shaft 708 will be swung in the same direction by link 706 and arm 707. The rocking of shaft 708 will swing arm 709 and its counterpart at the other side of the machine, thus moving rod 710 against the projecting tails 562^A of all the latches 562, thereby swinging all of said latches clear of the ends of parts 18^A. If under these conditions a numeral key is depressed, latch 562 will not act to set pawl 11^A, and therefore when the pawls 11^A are swung about their axis 4, and the type plate 37 is correspondingly elevated to printing position, the gear wheels 1 and type wheels 3 will not be rotated and no addition will be performed, but none of the other parts of the machine will be affected, and consequently the amount represented by the key depressed will be printed. Thus the machine remains a printing machine but not an adding or computing machine. The lower arm of said bell crank lever 705 is connected by bar 711 with arm 712, which is fastened solidly to shaft 713 outside of the side frame B'. Shaft 713 extends through side frame B' into the opposite, similar side frame, and turns in said side frames. Arm 714 is fastened solidly on said shaft 713 just inside of side frame B', and a duplicate thereof is fastened to said shaft just inside of the opposite side frame. Connecting said arm 714 and its counterpart, is a rod 715 extending under the noses of the several hammer operating latches 106.

When lever arm 705 is thrown backward in the direction opposite to that indicated by the arrow, it will lift link 711 and arm 712, thereby rocking shaft 713 and swinging arm 714 and its counterpart upward, causing rod 715 to press against the noses of all the latches 106 and swinging them clear of the arms 109^A. If now a key is depressed, the amount represented thereby will be added on the adding wheels or type wheels, but as the latches 106 cannot operate hammers 109, no printing will be performed. Thus the machine becomes an adding, but a non-printing machine. It will be observed that the swinging of said hand lever in the direction of the arrow, for disabling the computing mechanism, swings the rod 715 away from latches 106, leaving the printing mechanism unaffected; and similarly the swinging of the hand lever in the direction opposite to the arrow, for disabling the printing mechanism, swings the rod 710 away from the tails of latches 562, leaving the adding or computing mechanism unaffected.

In Fig. 3, I have illustrated my non-add, non-print device adapted to a machine having modified mechanism for operating the adding wheels. Bar 561 is changed in form as shown, having a shoulder near its upper end to engage and actuate the upper arm of part 18^A, and a shoulder at its lower end to engage latch 562^A, normally held in the position shown in the drawing by spring 560^A. When a key is depressed, swinging crank 560 and latch 562^A downward, bar 561 is pulled down, thereby lifting lock 18 and setting pawl 11^A. Other details of this modified mechanism form the subject of, and are more fully described in, another application to be filed simultaneously herewith, and are not material to an understanding of the present invention. By disabling or disconnecting latch 562^A the operation of the adding or computing wheels will be cut out. This is accomplished as follows: Rod 706^A connects lever 705 with arm 707^A which is fast on shaft 708^A. Arm 709^A is fastened solidly on said shaft 708^A inside of side frame B' and is connected by rod 720 with the upper arm of bell crank lever 721, which is fast on shaft 722 extending across the machine and journaled in the side frames. A duplicate of the lower arm of bell crank 721 is fastened on shaft 722 just inside the side frame of the machine opposite to 721. Rod 723 extends between said bell crank 721 and said duplicate arm, across the projecting tail pieces of all the latches 562^B. When the lever 705 is thrown forward in the direction of the arrow, it will press the rod 723, by means of the above described connecting mechanism, against the tails of all the latches 562^B thus moving them clear of the shoulder on bars 561, thereby cutting out the adding mechanism, but leaving the machine in condition to print.

I claim:

1. In a typographical computing machine, a series of numeral wheels, mechanism to actuate said numeral wheels, printing devices, mechanism to actuate said printing devices, a shipper, connections between said shipper and said numeral wheel actuating mechanism adapted to disable the latter, and connections between said shipper and said printing device actuating mechanism adapt- 130

ed to disable the latter, both of said disabling connections being controlled by said single shipper, and each being adapted when operated to render inoperative its corresponding actuating mechanism without affecting the other actuating mechanism.

2. In a typographical computing machine, a series of numeral wheels, mechanism including a set of latches normally in operative position to actuate the numeral wheels, printing hammers, mechanism including a set of latches normally in operative position to actuate the printing hammers, and means to move the latches of one of said 15 mechanisms to inoperative position without affecting the other.

3. In a typographical computing machine, a series of numeral wheels, mechanism including a set of latches normally in operative position to actuate the numeral wheels, printing hammers, mechanism including a set of latches normally in operative position to actuate the printing hammers, and means operated by a single shipper to move 20 the latches of either of said mechanisms to inoperative position without affecting the other.

4. In a typographical computing machine,

a series of numeral wheels, mechanism including a set of latches normally in operative position to actuate the numeral wheels, printing hammers, mechanism including a set of latches normally in operative position to actuate the printing hammers, and a movable rod extending across each of said sets of latches, either rod adapted to move its set of latches to inoperative position without 30 affecting the other.

5. In a typographical computing machine, a series of numeral wheels, mechanism including a set of latches normally in operative position to actuate the numeral wheels, printing hammers, mechanism including a set of latches normally in operative position to actuate the printing hammers, a movable rod extending across each of said sets of latches, and mechanism operated by a single shipper adapted to actuate each of said rods to move either set of latches to inoperative 40 position without affecting the other.

Signed by me at Boston, Massachusetts, this seventeenth day of July, 1912.

GEORGE WALKER.
